WATCHCASE

Joseph Granat, San Francisco, Calif.

Application December 10, 1951, Serial No. 17,678

Term of patent 14 years

(Cl. D42—8)

To all whom it may concern:

Be it known that I, Joseph Granat, a citizen of the United States, residing at San Francisco, State of California, have invented a new, original, and ornamental Design for Watch Case, of which the following is a specification, reference being had to the accompanying drawing, forming a part hereof.

Fig. 1 is a plan view of the watch case, showing my new design.

Fig. 2 is a side elevational view of the watch case of Fig. 1.

Fig. 3 is a view of the rear side of the watch case of Fig. 1.

The dominant features of this design are shown in full lines on the drawings.

I claim:

The ornamental design for a watch case, substantially as shown and described.

JOSEPH GRANAT.
